OTTO CRONAU, OF NEW YORK, N. Y.

RELIEVING ATTACHMENT FOR LATHES.

1,350,361.

Specification of Letters Patent. Patented Aug. 24, 1920.

Application filed July 23, 1919. Serial No. 312,742.

To all whom it may concern:

Be it known that I, Otto CRONAU, a citizen of Germany, and a resident of New York, in the county of New York and State of New York, having invented certain new and useful Improvements in Relieving Attachments for Lathes, do hereby declare that the following is a full, clear, and exact description of the same.

10 This invention relates to relieving attachments for lathes and has for its primary object to provide improved means for relieving milling cutters, reamers, taps, dies, etc., whereby they are intermittently moved 15 out of operative relation to the tool.

It is another object of my invention to provide a very novel lathe attachment of this character wherein the work piece is oscillatably suspended, and means for continuously imparting axial rotation to the work 20 of an ordinary engine lathe.

My invention further contemplates the provision of simple and effective means for urging the work piece into contact with the 25 tool.

It is also a further general object of my invention to provide a very simple mounting and arrangement for the oscillatable and continuously rotating work whereby the 30 work may be operatively connected to the head stock of the lathe in a direct manner and with a minimum of lost motion, the attachment as a whole being applicable to the ordinary metal working lathe without 35 necessitating any alterations in the latter.

With the above and other objects in view, the invention consists of an improved relieving attachment for lathes as characterized and in the form, construction and combination of its several parts as will be hereinafter more fully described and subsequently incorporated in the subjoined claims.

In the accompanying drawings wherein I have illustrated one practical embodiment 45 of my invention:

Figure 1 is an elevation partly in section showing a milling cutter operatively mounted between the oscillatable supporting brackets and the driving connection between the 50 axis of the cutter and the head stock of the lathe.

Fig. 2 is a fragmentary plan view.

Fig. 3 is a section taken on the line 3 of Fig. 1; and

Fig. 4 is an end elevation illustrating the 55 operating gearing for the cam member.

Referring in detail to the drawings where-in similar reference characters designate corresponding parts throughout the several views, 5 indicates similar end plates constituting a supporting frame for the several parts of the attachment to be presently referred to. These end plates are tied together and rigidly held in spaced relation to each other by means of the longitudinally 60 extending rods 6.

A supporting rod 7 is rotatably mounted at its ends in the frame plates 5, and upon this rod the depending brackets 8 are fixed at their upper ends by means of set screws 70 or other suitable means. These brackets are connected to each other by means of a rod 9 and preferably one of the brackets may be adjusted longitudinally with respect to the rods 7 and 9 to position the center pin 10 75 carried by said bracket relative to the driving spindle for the tool as will more clearly appear from the following description. Each of the bracket members is formed upon one side with a transversely extending arm 80 as indicated at 11 in Fig. 3 of the drawings, and the rod 9 is engaged in the ends of these arms.

The other of the bracket members 8 is formed at its lower end with a split sleeve 85 12 the spaced portions of which are connected by the clamping bolts 13. Within the sleeve 12 a second split sleeve 14 is engaged and a bushing 15 is disposed within the latter sleeve and constitutes a bearing for 90 one section 16 of a driving spindle. The adjacent frame plate 5 is formed with a hub extension 17 to receive the bushing 18 for a second spindle section 19. This latter spindle section is connected to the section 16 of the 95 driving spindle by means of the universal joint or coupling member 20.

21 designates a milling cutter or other work piece fixed on a mandrel or arbor 22, one end of which is mounted in a lathe dog 100 which is fixed by means of a set screw 24 in the arm 25 secured upon the end of the bushing 15. This end of the shaft is provided with a seat for the point 17 of the spindle section 16. The other end of the shaft 22 105 also has a cone bearing seat to receive the center pin 10.

The outer end of the spindle section 18 re-

ceives the center pin 26 of the head stock 27, said spindle being also mounted in the lathe dog 28 which is fixed to the head stock. The other frame plate 5 is provided with a seat for the center pin 29 of the tail stock 30 of the lathe.

Upon the section 18 of the driving spindle a gear 31 is fixed and meshes with a similar gear 32 mounted upon the stud shaft 33 which is mounted in the frame plate 5. This gear 32 carries a pinion 34 which is in constant meshing engagement with a gear 35 fixed on one end of a shaft 36 which is journaled in a suitable bearing 37 formed upon the frame plate. Upon the other end of the shaft a cam 38 is secured, said cam having a plurality of cam faces 39. I have indicated on the drawing six of these eccentric cam faces, though it will be understood that interchangeable cams may be provided having varying numbers of such eccentric faces. These eccentric faces of the cam 38 are adapted to coact with a lug 40 projecting from the bracket member 8 in which the spindle section 16 is mounted. To the arm 11 of this bracket the lower end of a contractile spring 41 is attached, the upper end of said spring being connected to an arm 42 fixed upon one of the rods 6. This spring normally acts to oscillate the bracket members in one direction and hold the lug 40 in contact with the eccentric faces of the cam 38.

Assuming that the cutter or other work has been assembled between the spindles 10 and 16, as shown in Fig. 1 of the drawing, it will be understood that this cutter is continuously rotated with respect to the tool mounted in a suitable tool post (not shown). During such rotation, rotation will also be transmitted through the medium of the gears 31, 32, pinion 34 and gear 35 to the cam 38, and as this cam is thus rotated in the direction indicated by the arrow in Fig. 3, the bracket members 8 together with the work mounted and supported therebetween will be swung or oscillated against the action of the spring 41 and the work thus relieved from engagement with the tool. As soon as the lug 40 moves off of the end of each eccentric face 39 of the cam, the spring 41 immediately acts to return the cutter or other work piece to its normal position in engagement with the tool. In this manner, there is obtained an intermittent relieving or backing-off movement of the work whereby the work will be accurately executed and during such movements the work is continuously rotated through the medium of the flexible driving connection between the shaft 22 and the head stock spindle. The universal joint member 20 permits of the necessary angular movement of the spindle section 16 with respect to the spindle section 19 without binding.

From the foregoing description considered in connection with the accompanying drawings, it will be seen that I have devised a very simple and positively operating relieving attachment for lathes and one which may be readily applied and used in connection with the ordinary lathe. The cam for oscillating the tool may be readily interchanged so as to obtain any desired number of the relieving movements in each rotation of the work. The means for operatively mounting the work between the oscillating brackets admits of the easy and quick removal of the work piece and the substitution of another work piece in place thereof. The arrangement of the driving connections between the work piece and the head stock spindle is also quite simple, not liable to get out of order, and affords a direct driving connection which is maintained during the oscillating movements of the work. Preferably I provide suitable thrust bearings indicated at 43 between the gear 31 and the frame plate 5.

While I have above described what I have found to be a very practical embodiment of my invention, it is nevertheless to be understood that the relieving attachment may also be exemplified in numerous other alternative constructions and I accordingly reserve the privilege of adopting all such legitimate changes as may be fairly embodied within the spirit and scope of the invention as claimed.

I claim:

1. A relieving attachment for lathes comprising a stationary frame adapted to be arranged between and supported by the head and tail stocks of a lathe, a work support oscillatably suspended in said frame, means for continuously rotating a work piece mounted in said support, and means driven by the head stock spindle for oscillating said support to intermittently relieve the work from engagement with the tool. 105

2. A relieving attachment for lathes comprising a frame adapted to be arranged between and supported by the head and tail stocks of a lathe, a work support oscillatably suspended in said frame, a flexible drive means for the work support mounted in said frame and driven from the head stock spindle, and additional means mounted upon said frame and operatively connected to said drive means coacting with the work support to oscillate the latter and intermittently relieve the work from engagement with the tool. 115

3. A relieving attachment for lathes comprising a frame adapted to be arranged between and supported by the head and tail stocks of a lathe, a work support oscillatably suspended in said frame, flexible drive means for the work support, including a part journaled in said frame and operatively engaged 125

100

110

130

with the head stock spindle, and means geared to said part and coacting with the support to oscillate the latter and intermittently relieve the work from engagement 5 with the tool.

4. In combination with a lathe a rotatable work support oscillatably suspended between the head and tail stocks of the lathe and normally having its axis disposed in 10 line with the axes of the head and tail stock spindles, a flexible driving connection between the head stock spindle and said support, and means geared to said driving connection to oscillate the work support and 15 intermittently relieve the work from engagement with the tool.

5. In a relieving attachment for lathes, a supporting frame, brackets oscillatably mounted on said frame, a rotatable work 20 mandrel mounted between the brackets and oscillatable therewith, means for continuously rotating said mandrel including a flexible spindle having a part mounted in one of the brackets, and means geared to 25 the other part of said spindle for oscillating the brackets and mandrel to intermittently relieve the work from engagement with the tool.

6. In a relieving attachment for lathes, a 30 frame, spaced brackets oscillatably mounted on said frame, a work mandrel rotatably mounted between the brackets and oscillat-

able therewith, means for continuously rotating said mandrel including a drive spindle having a section mounted in one of the 35 brackets and a section mounted in the frame, a flexible coupling between the spindle sections, and a cam geared to the latter spindle section and coacting with said bracket to oscillate the brackets and the shaft and intermittently relieve the work from engagement 40 with the tool.

7. In a relieving attachment for lathes, a frame, spaced brackets oscillatably mounted on said frame, a work mandrel rotatably 45 mounted between the brackets and oscillatable therewith, means for continuously rotating said mandrel including a drive spindle having a section mounted in one of the brackets and a section mounted in the frame, 50 a flexible coupling between the spindle sections, a cam geared to the latter spindle section and coacting with said bracket to oscillate the brackets and the mandrel and intermittently relieve the work from engagement 55 with the tool, and a spring connected to said bracket and acting to normally hold the spindle sections in axial alinement and to return the work to its effective position in engagement with the tool.

In testimony that I claim the foregoing as my invention, I have signed my name hereunto.

OTTO CRONAU.
